Specification for Design.

Patented Jan. 16, 1917.

Application filed June 14, 1915. Serial No. 34,094. Term of patent 7 years.

To all whom it may concern:

Be it known that I, FRANCIS M. BRINCKERHOFF, a citizen of the United States, residing at Englewood, county of Bergen, and State of New Jersey, have invented a new, original, and ornamental Design for Light-Screens, of which the following is a specification, reference being had to the accompanying drawing, forming part thereof.

Figure 1 is a top plan view of a light-

screen embodying my ornamental design; Fig. 2 is a side elevation of Fig. 1; and Fig. 3 is an end elevation.

I claim:

The ornamental design for a light-screen, as shown.

In testimony whereof I have hereunto signed my name.

FRANCIS M. BRINCKERHOFF.
